UNITED STATES PATENT OFFICE.

FRANK S. SWALM, OF BROOKHAVEN, MISSISSIPPI.

DESIGN FOR A SPOON:

SPECIFICATION forming part of Design No. 29,695, dated November 22, 1898.

Application filed November 1, 1898. Serial No. 695,241. Term of patent 7 years.

To all whom it may concern:

Be it known that I, FRANK S. SWALM, a citizen of the United States, residing at Brookhaven, in the county of Lincoln and State of Mississippi, have invented and produced a new and original Design for a Paper Spoon, of which the following is a specification, reference being had to the accompanying drawings, forming a part thereof.

Figure 1 is a plan view, and Fig. 2 is an edge view, of a spoon, showing my new design.

As shown in the drawings, the leading or material feature of my design consists of the ring-shape conformation A at the upper end or head of the handle B.

The spoon-bowl C is at the end of the handle opposite the ring A, and the latter is shown arranged with its center in line with the handle B, or, in other words, so the handle if prolonged would extend diametrically across and bisect the ring A, and same to be completely of paper.

Having thus described my invention, what I claim as new, and desire to secure by Letters Patent, is—

The design for a spoon, as herein shown and described.

FRANK S. SWALM.
